Primary Examiner — Angela J Lee(74) *Attorney, Agent, or Firm* — Kory D. Christensen; Stoel Rives LLP**CLAIM**

The ornamental design for an anesthesia machine with user interface, as shown and described.

DESCRIPTION

The single FIGURE is a front view of an anesthesia machine with user interface showing our new design.

The broken line showing of an anesthesia machine display, icons, and alphanumeric text is for illustrative purposes only and forms no part of the claimed design.

1 Claim, 1 Drawing Sheet
